FIG.1

FIG.4

FIG.2

FIG.3

FIG.5

FIGURE 1 is a perspective view of a keyboard instrument, showing my new design;

FIGURE 2 is a front elevational view thereof;

FIGURE 3 is a rear elevational view thereof;

FIGURE 4 is an elevational view of side not shown in FIGURE 1, and

FIGURE 5 is a bottom plan view thereof.

The dominant features of my invention reside in the portion in full line.

The conventional keyboard is fragmentarily shown by means of solid lines and is continuous across the manual as indicated by the dot-dash lines.

I claim:

The ornamental design for a keyboard instrument, substantially as shown and described.
